UNITED STATES PATENT OFFICE

RALPH J. FRICK, OF BURLINGTON, IOWA.

ELECTRICALLY-PROPELLED TOY AUTOMOBILE.

Application filed January 24, 1923. Serial No. 614,631.

To all whom it may concern:

Be it known that I, RALPH J. FRICK, a citizen of the United States, residing at Burlington, in the county of Des Moines and State of Iowa, have invented an Electrically-Propelled Toy Automobile, of which the following is a specification.

This invention relates broadly to an improved electrically driven vehicle, and it has more particular reference to a self-propelled toy which is constructed to simulate a full-sized conventional automobile, the present toy being of a size which is particularly adaptable for a child.

The principal advantage of the present invention is that it is so constructed to render it comparatively inexpensive to both the manufacturer and the user, the same possessing the general contour and lines of a full-sized high priced car, but being exceedingly light in weight and such in construction that it can be safely driven by small children.

In carrying out the invention, it has been my principal aim to equip it with a novel foot-actuated motor-controlling switch which is disposed on the foot-board of the machine so as to simulate the customary foot-accelerator. As will be later observed, the switch is automatic in its operation, that is, it is automatically returned to circuit-opening position the moment the operator's foot is disengaged therefrom. Hence, it is compulsory for the operator to maintain his foot on the so-called accelerator so long as the machine is in operation. In the event that the child should by accident be thrown from the machine due to overturning or otherwise, the current to the motor immediately ceases and the car stops.

It is another feature of the invention to associate with the aforesaid foot-actuated switch, a positive brake which is active on the armature shaft of the motor, means being included in the electric circuit for immediately applying the brake the moment that the foot-controlled switch is opened, and for disengaging the brake as soon as pressure is applied to the foot-actuated means for the switch.

I aim further to utilize a unique switch in association with the foot-operated means herein referred to, the switch including separate selectively operated contacts, one of which imposes resistance in the circuit when in use, and the other of which disposes of

this resistance. Hence, a vehicle is provided which has two speeds, the speed being controlled at the will of the driver.

Numerous other structural features and advantages of the invention will become evident from the following description.

In the accompanying drawings forming a part of this specification and in which like numerals are employed to designate like parts throughout the same:

Figure 1 designates a side elevation, with portions in section, of a toy automobile constructed in accordance with this invention.

Figure 2 represents an enlarged detail sectional view, with portions in elevation, of the so-called foot-accelerator and switch.

Figure 3 is an enlarged detail view taken substantially on the line 3—3 of Fig. 6.

Figure 4 is an enlarged longitudinal section through the transmission gearing, the view being taken substantially on the line 4—4 of Fig. 6.

Figure 5 is an enlarged section taken on the line 5—5 of Fig. 1.

Figure 6 is a top plan view of the toy.

Referring now to the drawings in detail, it will be observed that the reference character 1 designates generally the metallic body of a miniature automobile, this body being shaped, as before stated, to simulate, as nearly as possible, the body of a full-sized conventional automobile. While the body shown resembles an ordinary "racer", it is of course understood that it could well be constructed to simulate any of the other various styles of machines.

In the showing, the body is provided with a hood 2, at the forward end of which is a dummy radiator 3. In front of the occupant's seat, is the usual inclined steering rod column 5, at the upper end of which is the usual hand-wheel 6. Below the steering column is the inclined foot-board 7.

The body 1 is supported on a chassis 8 such as is better seen in Fig. 6, and the chassis in turn is supported by a plurality of rubber-tired metal disk-wheels 9. While on the structure of the chassis, attention may well be confined to Fig. 6, wherein it will be observed that the same includes the usual longitudinal side bars 10, cross braces 11, a transverse reinforcing member 12, front and rear axles 13 and 14, and a special motor-supporting rod 15 which is disposed transversely between the side bars just in advance of the rear axle. Also, as seen better

in Fig. 1, the forward end of the body carries suitable springs 16, which are connected intermediate their ends with the front axle. The rear end of the body is provided with 5 hangers 17 which are connected with bearings 18. The hangers are bolted or otherwise secured to the side bars of the chassis (see Fig. 5) and the rear axle is rotatably received in the bearings. It will be further observed from Fig. 5 that the left-hand wheel is an idler, whereas the opposed wheel is keyed to the axle to be driven thereby. With this arrangement, the relative 10 difference in speeds of the rear wheels is compensated for when turning corners and the like.

It has been before intimated that the toy operates under the influence of motive power, preferably electricity. In carrying 20 out this end, I provide a comparatively small battery 19 which is suitably supported on the chassis and is disposed within the aforesaid hood. In practice, the hood will be constructed of sections to permit access to 25 be had to the battery for removing it, and the sections of the hood, as shown will be provided with suitable retaining clips. In association with the battery, is a motor 20 which is supported upon the aforesaid rod 15 in any appropriate manner. This motor 30 is supplied with a driving armature shaft 21 which extends laterally from one side and as seen more clearly in Fig. 3, there is a brake drum 22 keyed on the armature 35 shaft. A brake band 23, which is secured to the motor as at 24, surrounds the drum, the free ends of the band being connected together by a spring 25 which serves to normally contract the band about the drum to 40 apply the braking action. Supported from an ear 26 on the motor is a control lever or arm 27 which is pivoted between its ends on the ear as seen and is connected at its lower end to one of the ears of the brake 45 band. It is desired to provide means for actuating the lever 27 in a manner to release the band at a predetermined time and in accomplishing this end, I provide an electro-magnet 28 which is supported in a cylinder 50 mounted on the motor. The core of the magnet is disposed in a position adjacent the upper free end of the lever 27 and when the magnet is energized as will be seen later, the lever 27 is rocked upon its pivot in a 55 manner to engage its upper end with the core of the magnet. Such movement of the lever releases the brake band against the action of the spring 25 and permits free rotation of the armature shaft. At this point, 60 it is thought convenient to state that the electro-magnet is provided with binding posts 29 and 30. A wire 31 is connected with the post 29 at one end and is connected at its opposite end to a detail to be later described. There is also a comparatively short

wire 32 and this is connected with the post 30 and with a third binding post 33 on the motor. To the other binding post 34 of the motor, another wire 35 is connected. As seen from Fig. 1, the wire 35 leads directly 70 to one of the binding posts on the aforesaid battery.

Considering further the electric motive power, I now direct attention to Fig. 2 wherein I have shown the foot-operated circuit-control means enlarged. The means under consideration preferably comprises a plunger 36 which passes slidably through an inclined cylinder 37 on the aforesaid foot-board. Any suitable means may be employed for providing a connection between the cylinder and foot-board. Also, the cylinder itself may be of any suitable construction, for instance, as shown to permit access to be had to the interior. It is to be 80 observed that the lower end of the plunger 36 extends beyond the corresponding end of the cylinder and the adjacent end of the aforesaid wire 31 is detachably connected thereto as indicated at 38. The upper end of the plunger also extends beyond the corresponding end of the cylinder and the extended portion is surrounded by a coiled spring 39 which bears at one end against the cylinder and at its opposite end against a head 40 which constitutes a foot-piece. Inside of the cylinder, the plunger is equipped with a shoulder 41 which abuts the upper end of the cylinder to limit the 85 sliding movement of the plunger in one direction. With this arrangement, it is obvious that the spring 39 serves to maintain the plunger in raised position as shown. On the outside of the cylinder are vertically spaced binding posts 42 and 43 respectively 90 which are bridged by a connector 44 of electro-conductive material. There is also an intermediate binding post 45 carried by the cylinder. A resistance coil or wire 46 is connected at one end with the upper post 42 and at its opposite end with the intermediate post 45 and the last named post is equipped with a contact 47 with which a coacting part 48 on the plunger is engageable. To the lower binding post 43, another contact 49 is 100 connected. These contacts are vertically spaced and are adapted to be selectively engaged by the part 48.

It is yet to be pointed out that (as seen in Fig. 4) a train of transmission gears is disposed between the aforesaid supporting rod 15 and the rear axle, these gears being in constant mesh and being housed in a single casing 50 which is suitably supported at its front end from the rod 15 and is supported at its opposite end by the rear axle. The gear 51 receives motion from a pinion 52 on the armature shaft and the gear 51 in turn imparts rotation to a larger gear 53 on the rear axle, through the medium of a pinion 110 120 125 130

54. With the arrangement shown, a fixed gear ratio is provided and the gears are in constant mesh so that the machine will not be permitted to run freely even on inclines.

5 Referring again to the electric circuit, it will be seen that the current passing through the wire 31 and plunger and several binding posts on the manually controlled device is carried back to the battery through the wire

10 55.

The operation of the automobile is as follows:—Upon applying pressure to the head 40 of the plunger 36 and moving it downwardly against the action of the spring 39, 15 the circuit closer 48 will be initially engaged with the upper contact 47 within the aforesaid cylinder 37. With this circuit closed, the motor will impart movement to the rear drive wheel through the medium of the 20 aforesaid gearing. At this time, it will be observed that the resistance provided by the coil 46 is thrown into the circuit and the machine runs at "low speed." Upon applying further downward pressure on the plunger, 25 the circuit closer 48 is engaged with the lower contact 49. As will be observed, with this arrangement of parts, the resistance is inactive and the machine runs at "high speed." Should the operator, by chance, be accidentally thrown from the machine, it 30 will be seen that as soon as his foot is released from the plunger, the spring will return it to its normal position, thus immediately opening the circuit and stopping the car. When the circuit is closed, the aforesaid magnet 28 is energized in a manner to rock the lever 27 on its pivot and to release the brake band. As soon as the circuit is 35 opened, however, the magnet is de-energized, the lever 27 released and the brake band automatically applied through the medium of the spring 25.

If desired, a suitable switch 56 may be supplied at a convenient point on the rear 40 of the machine for reversing the direction of movement of the machine. Also, in practice, any suitable structure may be provided at the forward end of the vehicle for obtaining the desired steering connection between 45 the rod 5 and front axle.

Although the specific details and their relative arrangements have been set forth, it is to be understood that variations may be resorted to within the scope of the adjoined claims.

55

I claim:

1. In an electrically controlled toy automobile, the combination of an electric propelling motor, a normally applied brake for arresting movement of the vehicle, an electric device for releasing said brake, an electric battery mounted upon the vehicle, conductors connecting said motor and said device in series and in circuit with said battery, and a spring-opened switch arranged in said circuit, said switch being positioned so as to be manually closed by the driver of the vehicle.

2. In an electrically controlled automobile, the combination of an electric propelling motor directly and permanently coupled to the driving axle of the vehicle, a normally applied brake for arresting rotation of said motor, an electric device for releasing said brake, an electric battery mounted upon the vehicle, conductors connecting said motor and said device in series and in circuit with said battery, and a spring-opened switch arranged in said circuit, said switch being positioned so as to be manually closed by the driver of the vehicle.

3. In an electrically controlled toy automobile, the combination of an electric propelling motor, a normally applied brake for arresting movement of the vehicle, a lever for controlling said brake, an electric magnet operable upon said lever to release said brake, an electric battery mounted upon the vehicle, conductors connecting said motor and magnet in series and in circuit with said battery, and a spring-opened switch arranged in said circuit, said switch being positioned so as to be manually closed by the driver of the vehicle.

4. A structure as specified in claim 1, and in which the spring-opened switch comprises a foot-depressed plunger located on the foot-board of the vehicle.

RALPH J. FRICK.
